UNITED STATES PATENT OFFICE

CURTIS C. SANER, OF HOUSTON, TEXAS.

ADJUSTABLE FORM FOR CONCRETE STRUCTURES.

Application filed May 31, 1923. Serial No. 642,428.

To all whom it may concern:

Be it known that I, CURTIS C. SANER, a citizen of the United States, residing at Houston, Harris County, Texas, have invented a certain new and useful Improvement 5 in Adjustable Forms for Concrete Structures, of which the following is a full, clear, and exact description, such as will enable others skilled in the art to which it appertains to make and use the same.

My invention relates to forms for use in the construction of concrete structures. It is particularly adapted for use in building chimney stacks but is capable of application 10 to other similar structures.

An object of my invention is to provide a form which is easily adjustable to different diameters and to different degrees of taper in chimney structures.

Another object is to provide a simple and efficient means of bracing the forms in adjusted position during the building operations.

Referring to the drawing herewith, 20 wherein like numerals of reference are applied to like parts in both the views, Fig. 1 is a top plan view of forms embodying my invention, arranged in proper position for constructing a chimney wall; Fig. 2 is 25 a side elevation thereof.

In carrying out my invention I provide a series of plates, preferably of heavy sheet metal, which may be arranged in upright position side by side to enclose a circular 30 space and serve as a retaining wall for molding chimneys of concrete or other similar material. These plates are rectangular in shape and somewhat elongated as to most of the plates, but in order to secure the proper taper or batter of the chimney I 35 contemplate using with the rectangular plates a predetermined number of plates which are slightly tapered so that the upper end thereof will be narrower than the

40 lower end. Obviously, if a chimney is to be constructed with a certain taper thereto, it will be necessary, in order to get the proper difference in diameter between the lower and upper ends of the wall formed 45 by the mold plates, to use a certain number of plates which decrease regularly in width from the lower to the upper end, and I contemplate spacing at approximately equal distances around the chimney the proper 50 number of tapered plates to secure the desired taper to the chimney. I am aware

that it is not new to use tapered plates in connection with a mold wall, such as is here described, but it is believed to be new to space mold plates of the proper taper at 60 spaced intervals about the chimney, along with other plates with parallel sides, so as to secure the proper taper to the chimney.

In the drawing I have shown two mold walls, making outer and inner walls 1 and 2 respectively. The outer wall 1 is made up of a plurality of plates of heavy sheet iron, which are approximately rectangular in shape, and may be of any suitable width. Among these plates 1 are a plurality of 70 plates 3 which are tapered slightly from the lower end toward the upper end so as to give the wall a taper upwardly in accordance with the desired form of chimney which is to be constructed. The plates 1 75 and 3 in the outer wall are connected together at their adjacent sides by means of an upright T-iron. The flat face of the said iron is placed in contact with the edges of the plates and is perforated at regular intervals to register with similar perforations in the plates, and bolts 4 are used to secure the T-irons 5 in position. There is a radially extending rib 6 along the said T-irons, and this rib is perforated longitudinally to allow the passage therethrough of tie bolts, as desired. At one point on the periphery of the wall the plates overlap as shown at 7, and the T-iron 5 at that point as well as the adjacent T-irons on the overlapping plate are connected by means of a series of tie bolts 8 at spaced intervals along the ribs. These tie bolts are threaded from end to end and have nuts thereon arranged one on each side of each of the said 90 ribs 5. By tightening these nuts the ribs may be moved toward each other and thus tighten the outer wall into the desired position.

The outer wall is spaced from the inner 100 wall by a series of cross pieces 10, which may be made of wood or similar construction of the desired length, to space the walls apart the desired thickness of the wall.

The inner mold wall 2 is made up of 105 plates, similar to those on the outer wall, some of which are tapered, and others not. The ribs 6 upon the T-irons which are used to secure the plates together project inwardly in a radial direction, and form supports 110 for bracing bars or straps 11. These straps 11 are arcuate in shape, and have their ends

bent inwardly at 12 and perforated to allow the passage therethrough of a tie bolt 13. As will be noted from Fig. 1 there is a tie bolt through each of the ribs 6 on the T 5 irons, arranged with a nut 14 on each side of the said rib. The outer end of the tie bolt on each side is passed through the inwardly bent end 12 of the strap 11 and a nut 15 at the end of said bracing strap is used 10 to force the end of the strap inwardly and compress the said strap longitudinally thereof so as to bow the central portion outwardly against the inner face of the wall 2, thereby acting to retain said plates resiliently 15 against the spacing bars 10. There are straps 11 between each of the said ribs. At one point 16 the plates overlap, as is the case in the outer wall, and to accommodate this variation in length of the bracing strap 20 I form a strap of two sections, as shown at 17, the inner ends of which are perforated and secured in the proper position by bolts 18. The length of the strap 17 is thus adjusted before it is tightened against the inner wall by means of the nuts 15, as previously described. This means of bracing the inner wall of the mold is particularly efficient and easily applied, and is an important feature of my invention. By means 30 of this bracing device the inner walls are retained in place without the necessity of the usual cross supports, and, as will be obvious, may be adjusted with very little difficulty, as many of these straps may be used 35 longitudinally of the plates as is necessary to properly brace the construction. It is contemplated therefore, that they will be used in about the same number as are the tie bolts 8 on the outer wall, and may be placed at desired points so as to properly 40 brace the complete wall. The further objects and advantages of this device will be apparent to one skilled in the art, without further description.

45 What I claim as new and desire to protect by Letters Patent is:

50 1. A form for molding concrete walls comprising inner and outer spaced walls made up of a series of oblong rectangular plates, having a predetermined number of

regularly spaced plates tapered upwardly, means to hold said plates together and means to brace the plates of the inner wall radially outward, comprising straps of metal secured along the line of connection 55 between the plates and means to compress said straps longitudinally thereof and thus force the said straps into supporting position against the plates in the manner described. 60

2. A form for molding concrete walls and the like comprising two spaced circular walls, approximately rectangular elongated plates, secured together along their sides by upright T bars to present radially extending ribs, having spaced perforations therein, means on the inner wall to brace said wall outwardly comprising resilient straps shorter than the width of said plates, threaded bolts extending through the perforations in said ribs and through the ends of the adjacent straps and means on said bolts to compress said straps to bow the said straps against said plates in the manner described. 70

3. In a form for molding walls of concrete and the like, two spaced circular walls made up of plates secured together along their adjacent sides by T-bars having radially extending ribs, a plurality of braces on the inner wall comprising curved resilient straps of metal secured adjustably between two of said ribs and means to compress said straps longitudinally thereof to bow the intermediate portion of said straps against said 85 plates in the manner described. 80

4. In a form for molding concrete walls and the like, two spaced circular walls made up of longitudinal plates secured together along their adjacent sides by T-irons presenting radially extending ribs, screw bolts between two of the outer ribs whereby said plates may be held inwardly, and straps of resilient metal between adjacent ribs on the inner wall and means to compress said straps longitudinally in the manner described. 90

In testimony whereof, I hereunto affix my signature, this the 26 day of May, A. D. 1923.

CURTIS C. SANER.
